Patented Apr. 29, 1919.

FIG.1,

UNITED STATES PATENT OFFICE.

EMIL GATHMANN, OF BALTIMORE, MARYLAND.

GRENADE-PROJECTILE.

1,301,929.

Specification of Letters Patent. Patented Apr. 29, 1919.

Application filed August 31, 1917. Serial No. 189,103.

To all whom it may concern:

Be it known that I, EMIL GATHMANN, a citizen of the United States, residing in Baltimore, State of Maryland, have invented a new and useful Improvement in Grenade-Projectiles, of which the following is a specification.

This invention relates to an improvement in a construction of a grenade projectile adapted to be exploded either at a predetermined time during flight or upon impact with any resisting target.

In time grenades or shrapnel projectiles of the usual type, as mostly used heretofore, it has been customary to provide a combination time and percussion fuse attached one to the other, or built together, the fuse as a whole being secured to the projectile at one end, usually the forward end. In projectiles of small caliber or diameter it is practically impossible to construct a combination time and percussion fuse so that the same may be attached to one another directly without unduly limiting the capacity of the projectile as a carrier of missiles or as a grenade. It is the primary purpose in the construction shown to construct small projectiles of a given weight, in grains, not pounds, as the projectile may be as light as one pound, with both a time and percussion fuse with a maximum chamber capacity of projectile. As under existing artillery conditions both types of fuses are often required in the same projectile, it is desirable to so equip the same.

It is further my invention, as stated before, to so construct the grenade projectile that it may carry a maximum load of shrapnel balls or other missiles or explosive material, and I accordingly have constructed a diaphragm or carrying plate in a novel manner, which insures greater rigidity to the projectile case and allows the same to be fired with high velocity, without danger of the projectile disintegrating, due to shock of discharge from gun.

With these and other objects, not specifically mentioned, in view, the invention consists in certain parts and constructions which will be hereafter fully described, and then specifically set forth in the claims hereunto appended.

In the accompanying drawings, which form a part of this specification, and in which like characters of references indicate the same or like parts—Figure 1 is a longitudinal cross-section of a projectile con-

structed in accordance with the invention, and Fig. 2 is a longitudinal plan of said projectile assembled in its cartridge case, the whole being termed in the art "fixed ammunition." The projectile being constructed in accordance with my invention, preferably carries both a time and percussion fuse at opposite ends of its longitudinal axis. In carrying the invention into effect, there is provided a case 3 having relatively thin walls 4 at its forward portion, and heavier walls 5 at its rear portion, and a collar like reduced diameter portion 6 at its rearward or base portion, a time fuse 7 being seated and mounted by means of screw threads or the like on the forward relatively thin portion 4 and a percussion fuse 8 being seated and mounted by means of screw threads or the like in the reduced diameter portion 6. The projectile carries a band 13, in a suitable band seat, of softer material than the walls of the projectile 4 and 5, which band is forced into the rifling grooves of the gun in the usual manner upon discharge of the projectile from the same. The projectile, as a whole, is preferably mounted in a brass cartridge case 14 for carrying the propellant charge of powder, and a primer 15 is held by said case 14 in the usual manner. In the preferred construction shown in the accompanying drawing, the time fuse 7 is made of a lighter material than the percussion fuse, and the body of the projectile, such as for example, aluminum. I am thus able to construct a projectile with both a time and percussion fuse mounted thereon, without increasing the standardized weights adopted by the Government for various sizes of projectiles, and still maintain a maximum carrying capacity of missiles or explosives within the projectile. The missiles are shown at 12 as being practically round balls, preferably of a heavy dense material, nesting one upon the other and carried by a diaphragm 10, which diaphragm has preferably integrally connected with it a flash tube 11. It should be noted that the forward walls 4 of the projectile 3 are made relatively thin, so as to allow a maximum space or chamber bore or projectile. They are however strong enough to resist the acceleration of the projectile from the bore of gun but should deform or burst upon explosion of the bursting charge 9 of the projectile. The diaphragm 10 has its forward seat R shaped to conform to the size and shape of the balls 12. A hol-

lowed shoulder W on the diaphragm 10 is constructed to help stiffen the thin portion 4 of the projectile 3 during gun acceleration. By making the diaphragm and the flash tube 5 integral, as shown, the construction of the same is considerably lightened and more space and weight can be given to the missiles or balls 12, as shown on the drawing, or to the explosive charge of the grenade. Dividing 10 the time and percussion fuse and making separate units of same, and constructing the time fuse of lighter material than the percussion fuse also increases the missile or explosive carrying capacity of the projectile 15 to a very large degree, especially in the projectiles of small or minor caliber where the weights are measured in grains, and small fuses must necessarily be employed if the value of the projectile as a grenade is to remain efficient. Other shapes fulfilling like 20 functions may obviously be employed, both in the diaphragm and rear contracted end of the projectile and in the fuse, in place of the preferred form shown in the drawing.

25 What is claimed is:

1. A grenade projectile for rifled cannon consisting of a cylindrical casing, having a contracted rear portion, a band on its outer cylindrical portion, a conical cylindrical gun 30 charge powder container having its forward portion seated upon the cylindrical casing aforesaid in rear of the said band, said container being fitted with a primer for ignition of the gun charge, the contracted rear portion of the grenade casing entering into but not being in contact with the said container, a percussion fuse mounted within and retained in said contracted rear portion of the casing and a time fuse mounted on and retained by the forward portion of the said casing.
2. A grenade projectile for rifled cannon

consisting of a cylindrical casing, having a contracted rear portion, a band on its outer cylindrical portion, a conical cylindrical gun 45 charge powder container having its forward portion seated upon the cylindrical casing aforesaid in rear of the said band, said container being fitted with a primer for ignition of the gun charge, the contracted rear portion of the grenade casing entering into but not being in contact with the said container, a percussion fuse mounted within and retained in said contracted rear portion of the casing and a time fuse mounted on and retained by the forward portion of the said casing, in combination with retaining means 50 for the time fuse having less structural resistance and being of a weaker material than the retaining means of the percussion fuse. 55

3. A grenade projectile for rifled cannon consisting of a longitudinal casing, having a contracted rear portion and a band on its outer cylindrical portion, in combination with a percussion fuse mounted within and 60 retained in said contracted rear portion of the casing, and a time fuse mounted on and retained by the forward portion of the said casing.

4. A grenade projectile for rifled cannon 70 consisting of a cylindrical casing, having a contracted rear portion, a band on its outer cylindrical portion, in combination with a percussion fuse mounted within and retained in said contracted rear portion of the cas- 75 ing, and a time fuse mounted on and retained by the forward portion of the said casing, the retaining means for the time fuse having less structural resistance than the retaining means of the percussion fuse. 80

In testimony whereof I have signed my name to this specification.

EMIL GATHMANN.
